UNITED STATES PATENT OFFICE.

OSCAR C. BEACH, OF LOS ANGELES, CALIFORNIA, ASSIGNOR TO FREDERICK W. BRAUN,
OF LOS ANGELES, CALIFORNIA.

KEYING DEVICE.

1,074,343.

Specification of Letters Patent. Patented Sept. 30, 1913.

Application filed December 9, 1909. Serial No. 532,267.

To all whom it may concern:

Be it known that I, OSCAR C. BEACH, a citizen of the United States, residing at Los Angeles, in the county of Los Angeles and State of California, have invented a new and useful Keying Device, of which the following is a specification.

This invention relates to a keying device especially adapted for disk pulverizers and the object is to provide a novel means for detachably securing the revolving disk to its shaft.

Figure 1 is a longitudinal vertical section with the parts all in operative position. Fig. 2 is a plan view in detail of the disk supporting head.

Carried on shaft 7 is a head 19 which is formed with an annular groove 20 which receives an undercut flange 21 with a beveled edge formed on the rotating disk 1. Set screws 22 in the head 19 engage the undercut flange 21 and hold the disk 1 from slipping out, while a pin 23 in the head 19 en-

gages in the flange 21 and prevents the disk 1 from turning on the shaft 7. By slightly loosening the set screws the disk may be removed from the head, while when the screws are in engagement with the flange, the beveled portion of the flange forms a positive means for retaining the disk.

What I claim is:

In a keying device, a coupling comprising a disk having an undercut flange with a beveled edge, a head having an annular recess which receives said undercut flange, screws extending through said head and engaging the beveled edge of said flange, and a pin extending from said head into the body of said flange.

In testimony whereof, I have hereunto set my hand at Los Angeles, California, this 27 day of November 1909.

OSCAR C. BEACH.

In presence of—

J. A. HANLEY,
H. D. MACKINNON.
